UNITED STATES PATENT OFFICE.

ANNA SANDMEYER, OF NORTH YAKIMA, WASHINGTON.

SEWING-MACHINE RUFFLER.

SPECIFICATION forming part of Letters Patent No. 793,161, dated June 27, 1905.

Application filed April 29, 1904. Serial No. 205,562.

To all whom it may concern:

Be it known that I, ANNA SANDMEYER, a citizen of the United States, residing at North Yakima, in the county of Yakima and State 5 of Washington, have invented a new and useful Sewing-Machine Ruffler, of which the following is a specification.

This invention relates to ruffler attachments for sewing-machines, and has for its object to 10 simplify and improve the construction and produce a device of this character by means of which "headed" ruffles may be produced upon the fabric without preliminary folding or folding and basting.

With these and other objects in view, which 15 will appear as the nature of the invention is better understood, the same consists in certain novel features of construction, as hereinafter fully described and claimed.

In the accompanying drawings, forming a 20 part of this specification, and in which corresponding parts are denoted by like designating characters, is illustrated the preferred form of the embodiment of the invention capable of carrying the same into practical 25 operation, it being understood that the invention is not necessarily limited thereto, as various changes in the shape, proportions, and general assemblage of the parts may be 30 resorted to without departing from the principle of the invention or sacrificing any of its advantages, and the right is therefore reserved of making all the changes and modifications which fairly fall within the scope of 35 the invention and the claim made therefor.

In the drawings thus employed, Figure 1 is a perspective view of a ruffler with the improvement attached. Fig. 2 is a perspective view of the improved ruffler-guide removed. 40 Fig. 3 is a perspective view representing a section of fabric as it appears when passing through the device, and Fig. 4 is a transverse section of the same. Fig. 5 is a view of the "blank" from which the improved device is 45 "struck up."

With ruffler attachments as heretofore constructed when it is desired to form a ruffle with a head or with a portion of the material folded over and united to the body of the material by ruffled or shirred stitching spaced

from the folded edge it is necessary to first fold the material over and preferably baste it to hold it while the ruffler is operating. The device herein shown and described is designed to automatically fold the material when it is 55 desired to form a headed ruffle thereon as fast as it is fed to the ruffler, and thus obviate the necessity for the preliminary folding and basting.

The improved device may be readily applied to any of the various forms of rufflers manufactured, but for the purpose of illustration is shown applied to an approved form of such devices, in which—

10 is the ruffler presser-foot; 11, the operating-lever; 12, the ruffler feeding mechanism, and 13 the bracket by which the ruffler-guide is attached.

The improved device herein shown and described takes the place of the ordinary ruffler-guide and is formed from a single sheet of suitable metal bent into the proper shape and comprises a base portion 14, having the needle-aperture 15 and spaced fingers 16 of varying lengths through which the material is 70 "threaded" on its way to the ruffler feeding or "shirring" mechanism. Extending from one side of the base portion 14 is a portion 17, having means, such as a recessed flange 18, for engagement with the clamp-screws 19 or 75 the bracket 13. Extending from the portion 14 is a folder consisting of a plate 20, having the extremity 21 folded beneath the same and forming a folding-guide for the material in advance of its passage to the guide-fingers 16. 80

By this simple attachment the material is folded over the required distance to form the head 22 and passed between the portions 20 and 21 and then the portion of the material thus folded passed beneath the finger 16, conforming in length to the desired width of head, and above the portions of the base-plate adjacent to the fingers and inserted into the ruffling mechanism in the ordinary manner. Then as the ruffling progresses the folded 90 edge is drawn through the portion 20 21, thus automatically folding the material which is to form the head of the ruffle and producing a uniform width of head.

The device is very simple in construction, 100

can be readily applied to any of the various forms of rufflers manufactured, and will be a very useful and efficient attachment to a sewing-machine. By its use it is obvious that a 5 very material saving in time and labor will be effected.

The device may be manufactured in various sizes and of any desired or suitable kind of material.

10 As many of the fingers 16 may be employed as required, one for each width of the head 22 to be folded, as will be obvious.

Having thus described the invention, what is claimed is—

15 A folding and guiding attachment for rufflers, comprising a single sheet of metal bent to form a pair of superposed parallel arms, one of which is of less length than the other, for the greater portion of its width, the shorter,

20 upper arm having an upturned flange that is provided with a pair of ears for engagement by supporting devices, the remaining portion

of the upper arm being extended to about the length of the lower arm and being bent under and downward in a plane between the planes 25 of the two arms and parallel with both in order to form a folding-tongue, the lower arm being provided at one end with a notch forming a needle-passage, and the intermediate portion of said lower arm being provided with 30 slits, the metal between the slits being bent upward and disposed slightly above the general plane of the arm to form a plurality of guiding-tongues in a general vertical plane common to the folding-tongue and the needle- 35 notch.

In testimony that I claim the foregoing as my own I have hereto affixed my signature in the presence of two witnesses.

ANNA SANDMEYER.
